Primary Examiner — Prabhakar Deshmukh(74) *Attorney, Agent, or Firm* — Boyle Fredrickson, S.C.(57) **CLAIM**

The ornamental design of a laser tag transceiver module, as shown and described.

DESCRIPTION

FIG. 1 is a perspective view of a laser tag transceiver module showing our new design;

FIG. 2 is a top plan front elevation view thereof;

FIG. 3 is a bottom plan view thereof;

FIG. 4 is a right side elevation view thereof;

FIG. 5 is a left side elevation, view thereof;

FIG. 6 is a front elevation view thereof; and,

FIG. 7 is a rear elevation view thereof.

The broken lines indicate unclaimed portions and form no part of the claimed design.
